UNITED STATES PATENT OFFICE

GIUSEPPE GISOLFI, OF BROOKLYN, NEW YORK

DESIGN FOR AN ANCHOR FOR NIGHT CANDLE OR SIMILAR ARTICLE

Application filed October 20, 1930. Serial No. 37,317. Term of patent 14 years.

To all whom it may concern:

Be it known that I, GIUSEPPE GISOLFI, a citizen of the United States, residing in New York city, borough of Brooklyn, in the county of Kings and State of New York, have invented a new, original, and ornamental Design for Anchors for Night Candles or Similar Articles, of which the following is a specification, reference being had to the accompanying drawing, forming a part thereof, and of which Figure 1 is a plan view, and Fig. 2 is a view in side elevation.

I claim:

The ornamental design for an anchor for night candle or similar article as shown.

GIUSEPPE GISOLFI.
